CLARK F. BARB, OF GOLDEN, COLORADO.

APPARATUS FOR THE RECLAMATION OF LUBRICATING OILS.

Application filed August 18, 1925. Serial No. 50,952.

This invention relates to apparatus for the reclamation of lubricating oils and its primary object is to provide a simple system of co-operating devices which in a process of precipitation, evaporation and filtration or percolation, completely cleanses dirty waste oils such as those obtained in the operation of various machines and engines, and more particularly the internal combustion engines of 5 motor driven vehicles.

In the operation of engines of this character the lubricating oils become charged with gasoline, kerosene, water and solid hydrocarbons to such an extent as to render them 15 unfit for lubricating purposes. Frequent renewals of the lubricating medium are therefore necessary in order to maintain the machine in proper working order, and the used oils being unsuited for further use, have 20 heretofore been usually thrown away and wasted.

By the use of my invention these waste oils are rapidly and completely relieved of all 25 contaminating matter at an expense of operation so low that their reclamation is attended with considerable profit upon reuse in the place of fresh oils procured from the refinery, and inasmuch as the oils may by the use of my improved method be thus repeatedly 30 claimed, the formerly heavy expense of lubrication of a machine or engine is reduced to the minimum.

Further objects of my invention reside in 35 details of construction and a novel arrangement of parts as will appear more fully in the course of the following description made with reference to the accompanying drawings.

In the drawings in which like characters of 40 reference designate corresponding parts throughout the several views,

Figure 1 represents an elevation partly in 45 section of an apparatus suitable for carrying my improved reclamation process into effect;

Figure 2, a plan view of the apparatus, drawn to a smaller scale;

Figure 3, an enlarged vertical section through the evaporator of the apparatus, taken on the line 3—3, Figure 2; and

Figure 4, a transverse section of the evaporator along the line 4—4, Figure 3.

Referring more specifically to the drawings, 5 designates a reservoir for the material to be treated which in addition to storing the 60 material for subsequent treatment, functions

as a preliminary settling unit for the separation of water and solids by sedimentation.

The container is to this end equipped with an intake pipe 6 extending to within a short distance above its bottom, and with a drain 60 cock 7 for the removal of settled matter, and it is further provided with an overflow 8 for the conveyance of the liquid rising above the settling solids, to the second unit of the system.

A funnel shaped mouth at the upper end of the pipe 6 facilitates the supply of material to the container.

The second unit of the system above referred to, comprises a container 10 placed 70 with its top beneath a spout 9 that connects with the overflow of the reservoir 5. A shallow filter 12 is suspended from the rim of the container by a curved flange for the preparatory filtration of the oils, and it consists to 75 this end, of a pan provided with a perforated bottom and filled with a suitable filtering agent as for example, fuller's earth.

The second unit of the system also functions as a settling vessel and it has adjacent 80 its bottom a drain cock 13 for the discharge of precipitated matter.

The third and last unit of the system consists of an evaporator 14 and a filter 15 mounted one above the other upon a skeleton stand 85 16. The evaporator consists of a preferably cylindrical tank 17 placed axially in a horizontal position at the top of the stand. The tank is double-walled to provide a surrounding jacket 18 to be filled with a suitable insulating medium.

An opening 19 at an end of the tank near the top thereof is by means of a valve-controlled nipple 20 connected with a suction appliance as for example, a wet water pump 21 95 shown in Figure 1, and a second opening 22 at the opposite end of the tank near the bottom thereof, is equipped with a fitting for its selective connection with either the container 10, the filter 15 or an outlet for settled matter. 100

The fitting consists to this end of a cross 23 which by means of a pipe 24 is connected with the opening 22 at the bottom of the evaporator, a second pipe 25 connected with the cross has its orifice in the lower portion of 105 the container 10, above the level of the drain cock 13, a third pipe 26 leads from the cross to a point above the filter 15, and the fourth branch of the cross connects with a short pipe 27 for the discharge of sludge. 110

The pipes 25, 26 and 27 are provided with valves 28, 29 and 30, respectively, to control their use in the operation of the system.

An electric heater 31 extends lengthwise 5 in the evaporator, through an opening in an end thereof and connects with a convenient source of electricity, and a well 32 in the opposite end of the evaporator provides for the employment of thermometric appliance to 10 ascertain the heat of the evaporator in the operation of the system.

The filter 15 consists of an upright tank 33 filled with fuller's earth or other filtering compound as at 34, above a perforated partition 35. The space 36 between this partition and the bottom of the tank provides a chamber for the filtrate which is discharged from the filter by means of a drain-cock 37. A pan 38 beneath the filter may be employed to collect the liquid drawn from the filter through 20 the outlet controlled by the valve 37.

In the operation of the system as above described, the reservoir 5 is filled with the refuse oil to or above the point of overflow, 25 through the pipe 6. The oil rising to the overflow leaves a sediment of water and other impurities which as a preliminary in the separating process is from time to time discharged through the drain cock 7. If, when 30 the apparatus is not in operation, the contents of the reservoir remain undisturbed for sometime, the amount of preliminary sedimentation is, of course, materially increased.

35 The rising oil overflowing through the opening 8, passes through the first filter 12 into the container 10 where it is again subjected to a settling action. The filter 12 removes the coarser solids from the oil and any 40 matter settling in the container out of the filtrate, is discharged through the opening controlled by the drain cock 13.

The steps of the process so far described are conjointly preliminary to the main action in which the volatile foreign constituents of 45 the oil are removed by distillation and the remaining solid impurities of smaller size than those retained in the first filter, are separated by percolation of the liquid.

50 The oil deposited in the container 10 is for the above stated purpose drawn upwardly through the pipe 25 past the open valve 28, into the evaporator 14 by suction applied at the opening 19.

55 After the evaporator has thus been filled to the required extent, the valve 28 is closed and the normally open circuit of the electric heater is completed in a conveniently located switch to subject the contents of the evaporator to a vaporizing temperature (about 550° F.). The volatile foreign constituents of the contaminated oil such as gasolene, kerosene and coal oil are volatilized and drawn off by the suction applied at the opening 19, leaving 60 the oil relatively pure except for the finer

particles of carbon and other solids which remained in the liquid at the time it was admitted to the evaporator.

The connection between the heater and the source of electricity is next disconnected and 70 the batch of material in the evaporator is allowed to cool and settle for a considerable length of time, while the connection between the evaporator and the suction appliance is left open for the purpose of removing all remaining vapors of the diluting constituents of the oil. 75

Cooling reduces the odor of heated oil and at the same time aids in preventing gumming and clogging the filtering material in the subsequent percolation step and by permitting the contents of the evaporator to settle, the burden of the filter is lightened and its capacity proportionately increased. 80

When the oil has been sufficiently cooled 85 (200 degrees Fahrenheit is under ordinary conditions as low as is necessary to obtain the desired result), the valve between the evaporator and the suction device is closed and the drain valve 30 is opened for the removal of 90 settled sludge.

After substantially all of the settled solids have thus been removed, the drain valve is closed and the valve 29 in the pipe 26 leading to the main filter is opened and by the percolation of the oil through the filter medium, the remaining impurities are separated from the liquid. This completes the operation, the oil finally discharged into the pan 38 through the drain cock 37 being practically free from impurities and as well, if not better, adapted for lubrication as the product originally obtained from the refinery. 100

It is known that the reclamation of contaminated oils has been attempted heretofore 105 by distillation and filtration, and the present invention consists primarily in an improved method of distillation and in a sequence of actions co-operating to remove substantially all of the impurities of the contaminated oils without deteriorative effects 110 and at an operating expense which renders the process commercially practical and advantageous.

Having thus described my invention, what 115 I claim and desire to secure by Letters Patent is:

1. An apparatus for reclaiming contaminated oils comprising a reservoir having a drain cock for settled matter, an overflow for 120 said reservoir, a settling tank, a filter located adjacent the top of said settling tank, said filter adapted to receive the overflow from said reservoir, a drain opening for said settling tank, an evaporator, a pipe connecting 125 said evaporator with the lower end of said settling tank, a four-way valve located in said pipe, a pipe leading from said valve to a filter, said four-way valve adapted to control the passage of oil from said settling tank 130

to said evaporator, or from said evaporator to said filter, heating means for said evaporator and means for drawing the oil from the settling tank to said evaporator.

- 5 2. An apparatus for reclaiming contaminated oils comprising a combined reservoir and settling tank having a drain opening and an overflow, a second settling tank, a filter supported adjacent the upper end of said second named settling tank for receiving the overflow, a second filter, an evaporator, piping for connecting said second named settling tank with said evaporator, or said evaporator with said second filter, said evaporator pro-

vided with an outer spaced wall extending 15 completely therearound, insulating material between said walls, an inlet for the oil adjacent the bottom of said evaporator, an outlet opening adjacent the upper end of said evaporator, suction means connected with said last named opening, a heating element extending longitudinally of said evaporator adjacent its bottom, and a tubular extension from said outer wall extending into said evaporator for the reception of a thermometer. 20 25

In testimony whereof I have affixed my signature.

CLARK F. BARB.
